US0D1095216S

(12) **United States Design Patent** (10) **Patent No.:** **US D1,095,216 S**
(45) **Date of Patent:** **** Sep. 30, 2025**

(54) **FASTENING, SUPPORTING OR MOUNTING DEVICE**

(71) Applicant: **Buttonfix Limited**, Edinburgh (GB)

(72) Inventors: **Philip Mark Hall**, London (GB); **Brian John Watson**, London (GB); **Anthony Arthur Wills**, London (GB)

(73) Assignee: **Buttonfix Limited**, Edinburgh (GB)

(**) Term: **15 Years**

(21) Appl. No.: **29/907,176**

(22) Filed: **Jan. 4, 2024**

(30) **Foreign Application Priority Data**

Jul. 5, 2023 (EM) 015026943-0001

(51) **LOC (15) Cl.** **08-11**

(52) **U.S. Cl.**

USPC **D8/373**

(58) **Field of Classification Search**

USPC D6/553; D8/14, 71, 349, 354, 363, 373,
